UNITED STATES PATENT OFFICE.

LEON SAFFIAN, OF PHILADELPHIA, PENNSYLVANIA.

DOWN-SPOUT.

1,213,910.

Specification of Letters Patent. Patented Jan. 30, 1917.

Application filed September 16, 1916. Serial No. 120,519.

To all whom it may concern:

Be it known that I, LEON SAFFIAN, a citizen of the United States, residing at Philadelphia, in the county of Philadelphia, 5 and State of Pennsylvania, have invented certain new and useful Improvements in Down-Spouts; and I do hereby declare the following to be a full, clear, and exact description of the invention, such as will enable others skilled in the art to which it appertains to make and use the same.

This invention relates to water distribution, and more especially to down-spouts; and the object of the same is to provide 15 means whereby a down-spout can be cleaned out when it has become choked as with leaves, etc. This object I accomplish by inserting into the run of the spout a skeleton section, and surrounding the same with 20 a slidible sleeve, preferably having a vent orifice to permit the outlet of water in a congested spout without causing it to bank up therein and leak out against the adjacent wall.

25 The invention is applicable to spouts of various sizes and shapes as illustrated in the accompanying drawings wherein:—

Figure 1 is a front elevation of a corrugated spout of this improved construction, with the opening therein closed, Fig. 2 is a front elevation of a cylindrical spout with the sleeve raised to uncover the opening, Fig. 3 is a vertical section through the spout shown in Fig. 2, and Fig. 4 is a horizontal section on about the line 4—4 of 35 Fig. 2.

Only a portion of the down-spout needs to be considered, and in the drawings I have shown an upper section 1 which leads 40 down from the eaves-trough, and a lower section 2 directly beneath and alined with the upper section and leading down to any suitable waste, such as the sewer. The upper end of the lower section is shown as 45 having a bell mouth 3 which produces an upwardly facing internal shoulder 4, and within this section beneath such shoulder is any suitable form of spider, shown in Figs. 3 and 4 as a number of rods 5 across the section although I would not be limited as to this detail. Resting removably on the spider a strainer 6 is shown in Fig. 4, and it is quite obvious that this strainer could be replaced by one of finer or coarser mesh 55 as desired, its purpose being to prevent leaves from running down the spout and

choking the sewer or the trap which connects the down-spout with the sewer. However, the strainer may be omitted if desired.

Between the sections 1 and 2 is disposed what I call a skeleton section 10, the same being shown as having side arms 11 connected at their upper ends with the upper section 1, passing down inside and spaced 60 from the bell mouth 3, extending past the shoulder 4, and secured in any suitable manner as at 12 within the lower section 2. I have shown but two of these side arms, leaving a large opening 13 between them, 65 and the section 10 may well be arched over said opening at front and back as at 14, and the edges of the latter beaded to prevent the operator from being injured thereon. The upper end of the skeleton section 70 10 makes a smooth joint with the upper section 1, and surrounding these sections and slidible over said joint is a sleeve 15 whose lower end is of a size to closely embrace the arms 11 and pass down into the 75 bell mouth 3 onto the shoulder 4, and the length of this sleeve is such that when it is so disposed as seen in Fig. 1 it completely covers the opening 13 through the skeleton section and extends for some distance up 80 onto the upper run of the pipe. When slipped upward as seen in Fig. 2, it may abut against a joint or bead 16 in the upper section, and its lower end stands above the opening 13 as shown. This sleeve is by 85 preference provided with a vent hole 17, and over the same I preferably mount a nipple or spout 18, and the vent is so disposed that it comes opposite the opening 13 when the sleeve is depressed.

In use, this down-spout is built as usual, its upper run being connected with the eaves and the lower section with the sewer or waste, and its skeleton section is built in as the run of pipe is erected, the sleeve being placed thereon at the time. When now 100 this sleeve is depressed as seen in Fig. 1, the entire down-spout is intact and water flows down it as usual. If a strainer is employed, leaves or the like would catch thereon so 105 that they do not pass into the sewer. In time they may accumulate to such an extent that the spout will become congested and choked, and during some heavy rain water will bank up above the leaves within the 110 sleeve 15, and run out the vent. This gives the owner notice that the down-spout needs

attention, and yet he is advised of this fact without the usual injury to the dwelling which takes place when a down-spout becomes congested. Grasping the sleeve with 5 his hands, he now slides it forcibly upward along the skeleton section until it strikes the bead 16, when the opening 13 is completely uncovered and he has immediate access to the pile of leaves or other obstruction resting on the spider or strainer. These 10 he can remove by hand, replacing the strainer or not as preferred, and immediately he depresses the sleeve to its original position with its lower end inside the bell mouth and the down-spout resumes its proper function.

It will be seen that the strainer serves the double purpose of preventing leaves from 20 getting into the sewer or the trap, and causing the leaves to accumulate to such an extent as to form a dam or plug and purposely produce an overflow through the vent. The nozzle inclosing the latter directs the overflowing water away from the down-spout and the house. The vent therefore performs the double function of preventing trapped water from banking up in the run of the down-spout and flowing out its joints, and 25 also it gives visual notice when a plug has formed on the spider. The arms of the skeleton section perform the important function of rigidly connecting the upper and lower sections and holding them in strict alinement so that the sleeve can be 30 slid either way with ease, and also they constitute guides for said sleeve and direct its lower end accurately into the bell mouth when it is moved downward.

Copies of this patent may be obtained for five cents each, by addressing the "Commissioner of Patents, Washington, D. C."

What is claimed as new is:

1. A down-spout comprising an upper section, a lower section having a shoulder and a bell mouth above it, and a skeleton section secured at its upper end to the upper section and having arms extending down past the bell mouth and shoulder of the lower section and secured within the body of the latter; combined with a sleeve slidably mounted on the upper and skeleton sections with its lower end adapted to enter said bell mouth when the sleeve is depressed, the body of the latter having a vent opening, a nozzle surrounding the same, a spider within the lower section below its shoulder, and a strainer removably mounted on said spider. 55

2. A down-spout comprising an upper section, a lower section having a shoulder and a bell mouth above it, and a skeleton section secured at its upper end to the upper section and having arms extending down past the bell mouth and shoulder of the lower section and secured within the body of the latter; combined with a sleeve slidably mounted on the upper and skeleton sections with its lower end adapted to enter said bell mouth and rest on the shoulder when the sleeve is depressed, the body of the latter having a vent opening, and a strainer within the lower section below its shoulder. 65

In testimony whereof I affix my signature 70 in presence of two witnesses.

LEON SAFFIAN.
